UNITED STATES PATENT OFFICE.

ARCHIBALD A. PEARSON, OF MERRIAM, KANSAS.

DESIGN FOR A DISPLAY-CASING.

SPECIFICATION forming part of Design No. 31,211, dated July 11, 1899.

Application filed June 8, 1899. Serial No. 719,852. Term of patent 7 years.

To all whom it may concern:

Be it known that I, ARCHIBALD A. PEARSON, of Merriam, Johnson county, Kansas, have invented and produced a new and original Design for Display-Casings, of which the following is a full, clear, and exact description, reference being had to the accompanying drawings, forming part thereof.

My invention relates to a new and useful design for display-casings.

In the accompanying drawings, Figure 1 represents a front view, Fig. 2 a top view, and Fig. 3 a rear view, of a display-casing, showing my new design.

The leading or material feature of the design resides in its egg-like form, with a circular and substantially horizontally-arranged division-mark extending around the figure and a connecting division-mark extending generally in a vertical plane from the horizontally-arranged mark to the bottom of the figure, said two marks conjointly representing the letter T when the figure is viewed from the front, as shown in Fig. 1.

The circular horizontally-arranged division-mark divides the casing into a top portion or cap and a lower or body portion, and the latter is divided into two similar segmental wings by the vertically-arranged division-mark.

Minor features of the design reside in the irregular or saw-tooth form of the horizontal

and vertically-arranged division-marks and in a vertically-arranged division-mark at the rear side of the figure, the last-named mark extending from the horizontally-arranged division-mark to the bottom of the figure. 35

Referring to the drawings in detail, A designates the egg-shaped casing generally; B, the segmental cap or top portion; C, the lower or body portion generally, and D D segmental wings forming said lower or body portion. 40

E designates the circular horizontally-arranged division-mark, which divides the casing into a top or cap portion and a lower or body portion, and F the front division-mark, 45 extending in a vertical plane from the horizontal division-mark to the bottom of the figure, said division-marks E and F being of irregular or saw-tooth form.

G designates the rear division-mark, extending in a vertical plane from the division-mark E to the bottom of the figure. 50

What I claim is—

The design for a display-casing, as herein shown and described. 55

In testimony whereof I affix my signature in the presence of two witnesses.

ARCHIBALD A. PEARSON.
